UNITED STATES PATENT OFFICE

98,054

DESIGN FOR A SHOE

Pasquale Colella, Nahant, Mass., assignor to Colella & Leighton Shoe Company, Lynn, Mass.,
a corporation of Massachusetts

Application November 15, 1935, Serial No. 59,586

Term of patent 3½ years

To all whom it may concern:

Be it known that I, Pasquale Colella, a citizen of the United States, residing at Nahant, in the county of Essex and Commonwealth of Massachusetts, have invented a new, original, and ornamental Design for a Shoe, of which the following is a specification, reference being had to the accompanying drawing, forming a part thereof, in which

The figure is a view in perspective of a shoe showing my design. Both sides of the shoe have substantially the same appearance.

I claim:

The ornamental design for a shoe substantially as shown and described.

In testimony whereof, I have affixed my signature hereto.

PASQUALE COLELLA.
